CLAIM

The ornamental design for a puck force measurement tool, substantially as shown and described.

DESCRIPTION

FIG. 1 is a left side view of a puck force measurement tool showing our new design;

FIG. 2 is a top plan view thereof;

FIG. 3 is a bottom plan view thereof;

FIG. 4 is a front plan view thereof;

FIG. 5 is a rear plan view thereof; and

FIG. 6 is a side elevational view thereof taken from the right side of FIG. 2.

Fig. 2

FIG. 4

FIG. 5

FIG. 6
